UNITED STATES PATENT OFFICE.

LOTHAR R. ZIFFERER, OF RIDGEWOOD, NEW JERSEY.

RECEPTACLE.

1,247,058.

Specification of Letters Patent. Patented Nov. 20, 1917.

Application filed October 21, 1916. Serial No. 126,974.

To all whom it may concern:

Be it known that I, LOTHAR R. ZIFFERER, a citizen of the United States, residing at Ridgewood, county of Bergen, and State of New Jersey, have invented certain new and useful Improvements in Receptacles, of which the following is a specification.

This invention relates to an improved receptacle for garbage, refuse, waste, etc., and is concerned particularly with the means by which its cover may be operated and by which the interior of the receptacle is disinfected.

In the present receptacle I have sought to provide a simple and effective means for removing the cover preparatory to a deposit of garbage or other refuse within the receptacle; a frame in which the receptacle may be conveniently supported, and from which it may be readily removed, when desired; means secured to the cover for causing the diffusion of a disinfecting agent within the receptacle with each deposit of garbage or refuse therein; and a lock to prevent animals from gaining access to the interior of the receptacle. The invention consists also in numerous other features of construction and combinations of parts, as will more clearly hereinafter appear.

In the drawings:

Figure 1 is a side elevation of a receptacle embodying the present invention, dotted lines being used to represent the raised position of the cover;

Fig. 2 is a plan view of the receptacle with the cover closing the receptacle;

Fig. 3 is a perspective view of the receptacle frame, the receptacle being removed therefrom;

Fig. 4 is a front view of the receptacle alone, its bail being shown in raised position; and

Fig. 5 is an enlarged detail view in cross-section showing the disinfecting chamber secured to the under side of the cover.

The present invention may be regarded as consisting of two principal elements: (1) The receptacle proper, which I have designated as 6, and (2) the frame 7 in which the receptacle may be conveniently mounted. It should be noted, however, that the receptacle may be used either independently of the frame, or in conjunction therewith, according as may be desired. The receptacle is preferably cylindrical in form, having a

round body 8, a bottom 9, and a cover 10, capable of being removed from off the receptacle whenever desired.

Extending laterally from opposite sides of the upper portion of the receptacle body 60 are headed trunnions 11, to which the ends 12 of a bail 13 are pivotally secured. The bail ends consist each of two portions 14 and 15, the former of which extend inwardly toward the receptacle, and the latter of 65 which are disposed transversely to the trunnions, and are shaped each in the form of a hook (see Fig. 1.) When the bail is swung down upon the forward side of the receptacle, the hook ends 15 are brought into position to engage with pins 16, projecting from opposite sides of the cover 10. Each of the pins 16 is provided, furthermore, with a head 17, so that the hooks may not be accidentally disengaged from the pins 16. 70 The hooks 15 formed at the bail ends are thus seen to coöperate with the pins 16 to form a lock for the cover when the bail is swung to the forward side of the receptacle. Whenever there is no desire to make use of 80 this lock, the bail may be swung toward the rear side of the receptacle, in which position the hooked ends 15 are removed from engaging position with the pins 16, so that no interference is thereby offered to removal 85 of the cover.

Centrally upon the under side of the cover I have arranged a chamber 18 for the reception of a disinfecting agent, the bottom of this chamber being preferably 90 perforated (see Fig. 5.) An opening is provided through the cover immediately above this chamber, a spout 20 upstanding from this opening, and a cap 21 being fitted onto the spout. A disinfecting agent, in powder form for example, may be placed within the chamber 18, and each time the cover is replaced after depositing refuse in the receptacle, a slight amount of the disinfectant will be shaken through the perforated bottom 19 and come into contact with the receptacle contents to exert thereon a deodorizing or neutralizing action.

The receptacle frame 7, best shown in Fig. 3, consists of a plurality of upright supports 22, the lower ends 23 of which are shaped to provide legs for the frame. Circular bands 24 and 25 are secured respectively to the upper and lower portions of the supports 22. Additionally, between the for- 110

ward and rearward pairs of legs 23 transverse braces 26 and 27 respectively are arranged, and also across the band 25 from its front to its rear side a reinforcing brace 28 is secured. An upright brace 29 is also arranged upon the rear end of the frame, its upper end 30 serving as a pivotal support for a leaf member 31, which will presently be described. To the central portion of the brace 26 a link 32 is pivoted, its forward end projecting out and terminating in a pedal 33. A second link 34 is similarly pivoted to the brace 27, being likewise pivoted as at 35 to the rear end of the link 32. The pivotal connections of these links 32 and 34 with the braces 26 and 27 are sufficiently loose to permit of the links swinging freely in a vertical direction to the extent necessary for operating the cover.

Secured to the rear end of the link 34 is a vertically extending connecting rod 36, which at its upper end is pivotally connected with the rear extremity of the leaf member 31 which, as shown, is pivoted intermediate of its ends to the brace 29. This leaf member may consist of a single piece of spring material bent to provide upper and lower companion sections 37 and 38 respectively, in both of which are formed registering slots 39. The section 37 may, furthermore, be provided with crimps 40 in the region of its slot 39. The leaf member is arranged to coöperate with a guide 41 attached to the receptacle cover, and having upstanding walls or flanges 42 between which the leaf member may be secured. A locking pin 43 is revolvably secured to the guide 41, and when properly turned may be entered through the slots 39 in the leaf member. After being so passed through these slots, this pin can then be given a quarter turn, whereupon its head 44 will depress the section 37 and find rest within one of the crimps 40. In this position the head of the locking pin will be disposed transversely of the slots 39, so as to establish a secure connection between the leaf member and the receptacle cover.

Two members 46, each of which is formed with a slot as at 47, are carried by the band 24 to provide bearings in which the trunnions 11 may rest. These members are not intended to support the weight of the receptacle which normally is carried upon the braces 26, 27 and 28, but serve rather to lock the receptacle in proper rotative position relative to the frame to insure alinement of the cover operating parts.

In order to raise the lid to an upright position, it is necessary merely to apply foot pressure to the pedal 33 which normally remains in the position shown in Fig. 1. Pressure upon this pedal causes the links 32 and 34 to be tilted, and the connecting rod 36 to be moved downwardly, whereupon the rear

end of the leaf member 31 is drawn down, and its forward end secured to the cover is raised up. Under such circumstances the cover and its operating mechanism would occupy substantially the positions indicated 70 by the dotted lines in Fig. 1. I prefer that the cover should not swing upwardly past its center of gravity, so that it may of its own accord swing back into closed position when the operator has released his pressure upon 75 the pedal. It is manifest that with each operation of the cover the contents of the disinfecting chamber will be shaken sufficiently to cause a small portion thereof to spill into the can. By this means the receptacle will be disinfected with each deposit 80 therein of new matter.

From the foregoing description it will be seen that the receptacle of my invention may be very conveniently operated. The parts, 85 moreover, may readily be disassembled, and the receptacle proper be removed for purposes of cleansing or otherwise. The operating mechanism, moreover, is not only simple, but is so arranged as to readily connect 90 with the cover, or be disconnectible therefrom, as required.

I claim:

1. In combination, a receptacle, a cover for the receptacle, a frame within which the receptacle may be removably mounted, and cover operating means carried by the frame, consisting of a pair of loosely connected links pivoted to the lower portion of the frame and to each other, each link being 100 extended horizontally beyond the frame, a leaf member pivoted intermediate its ends to the upper portion of the frame, one end of the leaf member being detachably secured to the cover and the other end being extended horizontally beyond the frame, and a rod pivotally connected at one end to the extended portion of the leaf member and at the other end to the extended portion of one of the links, whereby the cover is caused 105 to swing upwardly when downward pressure is applied to the extended portion of the other link, substantially as described.

2. In combination, a receptacle, a cover for the receptacle, a frame within which the receptacle may be mounted, and cover operating means carried by the frame, consisting of a pair of links pivoted to the lower portion of the frame and to each other, each link being extended horizontally beyond the frame, a leaf member pivoted intermediate its ends to the upper portion of the frame, one end of the leaf member being secured to the cover and the other end being extended horizontally beyond the frame, and a connecting rod pivotally secured at one end to the extended portion of the leaf member and at the other end to the extended portion of one of the links, whereby the cover is caused to swing upwardly when 130

downward pressure is applied to the extended portion of the other link, substantially as described.

3. In combination, a receptacle, a cover for the receptacle, a frame within which the receptacle may be removably mounted, means carried by the frame for raising the cover, and a connection between the cover raising means and the cover, consisting of a slotted leaf member pivoted to the frame, a member upon the cover with which the leaf member may coöperate, and a locking device carried by the cover, arranged to secure the leaf member against longitudinal and lateral movement with respect thereto, said locking member being adapted to release the leaf member when desired, whereby the cover may be removed from the cover raising means, substantially as described.
- 20 4. In combination, a receptacle, a cover for the receptacle, a frame within which the receptacle may be removably mounted, means carried by the frame for raising the cover detachably connected thereto, whereby the receptacle and cover may be removed from the frame, and trunnions extended from the receptacle body on opposite sides thereof, to which the ends of a bail may be pivotally

secured, the frame being provided with slots within which the trunnions may lie to secure 30 the receptacle in a fixed position relative to the frame and operatively with respect to the cover raising means, substantially as described.

5. In combination, a receptacle, a cover 35 for the receptacle, a frame within which the receptacle may be removably mounted, means carried by the frame for raising the cover, and a connection between the cover and the cover raising means, consisting of a slotted 40 leaf member pivoted to the frame, a guide member upon the cover with which the leaf member may coöperate, and a swiveled pin arranged to extend through the leaf member slot, there being a head on the pin adapted 45 when properly manipulated to overlie the leaf member to hold the same securely upon the cover, and when manipulated to other positions to disconnect the cover from the leaf member, whereby the receptacle and 50 cover may be removed from the frame, substantially as described.
